INTERRUPTED THREAD TYPE, SLIDABLE JAW WRENCH

Eddie C. Christopherson, Newport, Wash., assignor of fifty per cent to William F. Killgore, Arcadia, La.

Application December 15, 1952, Serial No. 326,015

1 Claim. (Cl. 81—160)

This invention relates to new and useful improvements and structural refinements in wrenches, particularly pipe wrenches, and the principal object of the invention is to provide a means whereby a wrench of this type may be quickly and easily adjusted as to size or opening between the jaws thereof.

The above object is achieved by providing the customary threaded shank of the wrench with flat and unthreaded faces which are registerable with recesses in an actuating nut to permit the shank to slide until the nut is rotated to a position wherein the threads thereof engage the threads of the shank and lock the latter against sliding.

An important feature of the invention resides in the provision of means for locking the actuating nut against rotation, while another feature of the invention resides in the provision of resilient stop means for preventing the shank from being withdrawn from the handle of the wrench.

Some of the advantages of the invention lie in its simplicity of construction, in its efficient and expeditious operation and in its adaptability to economical manufacture.

With the above more important objects and features in view and such other objects and features that may become apparent as this specification proceeds, the invention consists essentially of the construction and arrangement of parts as shown in the accompanying drawings, in which:

Figure 1 is a fragmentary elevational view of the invention, the same being shown partly in section to reveal its construction;

Figure 2 is a transverse sectional view, taken substantially on the plane of the line 2—2 in Figure 1 and illustrating the actuating nut in its initial, locked position;

Figure 3 is a sectional view, similar to that shown in Figure 2, but illustrating the actuating nut in its ultimate, unlocked position; and

Figure 4 is an elevational view of the shank and coacting jaw used in the invention, this view being taken in the direction of the arrow 4 in Figure 1.

Like characters of reference are employed to designate like parts in the specification and throughout the several views.

Referring now to the accompanying drawings in detail, the invention is embodied in a pipe wrench which is designated generally by the reference character 10 and comprises a handle 12 including a stationary inner jaw 14 and a laterally projecting protuberance or sleeve 16, the latter being formed with an open ended bore 18 and with an opening or recess 20 intermediate the ends of the bore 18, as will be clearly understood.

The customary coacting outer jaw 22 is formed integrally with a shank 24 which is of an elongated, rectangular cross-section and is provided with screw threads 26. However, these screw threads are interrupted by a pair of flat, unthreaded side surfaces 28 of the shank, as is best shown in Figures 2 and 3.

A knurled, cylindrical locking nut 30 is disposed in the recess 20 and when the screw threads of this nut engage the threads 26 of the shank 24 (as shown in Figure 2), the shank is prevented from sliding in the bore 18 in which it is positioned.

However, the nut 30 is formed with a pair of recessed, unthreaded portions 32 which slidably receive therein

2

the threaded side surfaces 26 of the shank 24 when the nut 30 is rotated through approximately 90 degrees to the position shown in Figure 3. In this position, the shank 24 is free to slide in the bore 18 to quickly and easily adjust the spacing between the wrench jaws 14, 22.

It is to be noted that the threads 26 of the shank 24 are beveled as indicated at 34 in Figures 1 and 4, so that the threaded portions of the nut 30 may be easily engaged therewith, when the nut is rotated to its locked position.

Means is provided for locking the nut 30 against rotation, said means including a keeper pin 36 which is slidably disposed in a bore 38 in the handle 12 and is pressed by a compression spring 40 into the recess 20 so as to engage the nut 30. The spring 40 abuts a plug 42 in the bore 38 and the nut 30 is provided in the outer surface thereof with a pair of circumferentially spaced keeper seats or sockets 44 to selectively receive the projecting portion of the keeper pin 36 when the nut is either in its operative or in its inoperative position. The nut 30 is also provided with a smooth groove 46 which extends circumferentially between the keeper seats 44 and provides a track for the keeper pin 36 while the nut is being rotated from one position to the other. Of course, the seats 44 are deeper than the groove 46 so as to sustain the nut against rotation when the keeper pin is disposed therein.

The shank 24 is preferably inscribed at one side thereof with a scale 50 which is preferably graduated so as to correspond to the spacing between the wrench jaws 14, 22, whereby the size of "opening" of the wrench may be readily determined.

Means is also provided for preventing the shank 24 from being withdrawn from the bore 18, this means consisting of a headed screw 52 which is mounted at the free end of the shank and carries a washer 54 pressed by a spring 56. Under normal conditions, the washer 54 abuts the adjacent end of the shank 24, but when the shank is slid in an upward direction as shown in Figure 1, the washer 54 will come in abutment with the protuberance or portion 16 of the handle 12 so as to prevent the shank from being withdrawn from the bore 18. The spring 56 will permit the washer 54 to yield to some extent, so as to eliminate excessive impact or shock.

It is believed that the advantages and use of the invention will be clearly understood from the foregoing disclosure, and accordingly, further description thereof at this point is deemed unnecessary.

While in the foregoing there has been shown and described the preferred embodiment of this invention, it is to be understood that minor changes in the details of construction, combination and arrangement of parts may be resorted to without departing from the spirit and scope of the invention as claimed.

What is claimed as new is as follows:

A pipe wrench comprising: a handle, a stationary inner jaw on one end of said handle, a longitudinal sleeve on the handle, a shank mounted for sliding adjustment in said sleeve, an outer jaw on one end of the shank cooperative with the inner jaw, means for adjusting the shank, a headed screw threadedly mounted longitudinally in the other end of the shank, a washer slidably mounted on the screw and engageable with the sleeve, and a coil spring on the screw between the head thereof and the washer, said screw, washer and spring constituting adjustable stop means engageable with the sleeve for yieldingly limiting sliding movement of the shank in one direction.
